UNITED STATES PATENT OFFICE

JOHN A. SCHAUSS, OF NORWALK, OHIO, ASSIGNOR TO THE SCHAUSS FURNITURE CO.,
OF NORWALK, OHIO, A CORPORATION OF OHIO

CHAIR

Application filed September 1, 1928. Serial No. 303,407.

This invention relates to furniture.

This invention has utility when incorporated in variable position seats or chairs, especially of the upholstered type having reclining convenience.

Referring to the drawings:

Fig. 1 is a side elevation of a chair frame in normal set up position under the invention herein;

Fig. 2 is a view of the frame of Fig. 1, with the chair shifted to a reclining convenience position, as to the position in Fig. 1;

Fig. 3 is a view in rear elevation of the frame of Fig. 1;

Fig. 4 is a section of the chair on the line IV—IV, Fig. 3; and

Fig. 5 is a detail view from the rear of the chair frame rear leg pair assembly.

Rectangular seat comprises front bar 1, side bars 2 therefrom extending to rear cross bar 3. From the rear portions of the side bars 2 of the seat rises a pair of chair back side members 4 having connecting strips 5, 6, 7, 8, therebetween from the top downward. Extending forwardly from an intermediate height position of the members 4, are chair arm top portions 9 forwardly terminating in drop portions 10, to the seat side bars 2. Depending from the two front corners of the chair seat 1, 2, 3, are front legs 11.

This chair seat, back, arms and front pair of legs are herein shown as a rigid assembly unit, for receiving usual upholstery, whether merely covered, cushioned, or overstuffed.

Upholstery chair seat 12 is accordingly at all times maintained in the same relatively rigid set up position to chair upholstery back 13. Back webbing or lining 14 as inwardly spaced from the rear covering 15 for the back provides space or pocket 16 in the back lower portion.

In the vicinity of this pocket 16, the chair back side members 4, are provided with upper pair of slot shaped seats 17, and lower pair of normally setting up or minor notches 18, and reclining convenience promoting or major notches 19. Countersunk in the members 4 inner sides are reinforcing wear plates 20 at the seats 18, 19.

In addition to this general chair assembly

unit, incomplete as to rear support, there is a relatively shiftable support, herein shown as comprising a pair of rear legs 21 connected as an auxiliary unit by intermediate tie piece or bar 22. In addition to this bar 22 between the legs 21 there is upper rod 23 and lower rod 24. These rods have their ends protruding beyond the legs 21, which legs 21 are spaced just within the spacing of the members 4.

With this auxiliary support assembled with the chair to complete such article of furniture, the rear leg pair has the legs 21 protrude from the lower opening 25 as the entrance to the pocket 16. In the assembly with the bar 24 as interfitting means coacting with the seats 81, the upholstered seat 12 of the chair may be in normal set up position and approximately horizontal. For obtaining a reclining convenience position for this chair, while still maintaining the relative positions between the portions thereof with which the occupant of the chair comes into position of repose, it is only necessary for one to give a slight lift and rearward shove to the chair in the region of the back thereof. The lift should be sufficient to have the rod 24 shifted clear of the notches 18, and the rearward shove should be sufficient to rock the rear leg pair on the rod 23 as an axis to bring the rod 24 into the vicinity of the entrance to the notches 19. With the chair now settling down at the rear, the rod 24 comes to chair rear sustaining position at the upper ends of the notches 19, in this telescoping of the rear leg pair up into the pocket 16 as directed by the sliding of the rod 23 in the slots 17. The chair back, seat and arms, are thus given a rearward tilt upon the floor extremities of the front legs 11 as an axis, bringing the chair back closer to the floor, as this chair comes into reclining convenience position.

For reset up of the chair, there is required a greater lift for the chair back or rear portion, with a slight forward pull, and then the settling down for the rod 24 to again seat in the notches 18. It is thus seen that there is possible quick position adjustments in a simple substantial structure.

What is claimed and it is desired to secure by Letters Patent is:

1. A chair comprising a seat and back unit, a rear leg unit movable relatively to the back unit, means for changing the angular relation of the chair and rear leg embodying guide slot means in one unit and a coacting lug on the other unit, a plurality of directing slots in one of said units, and an additional coacting lug in the other of said units positioned in one of said latter slots for determining one angular relation between the units and in a different latter slot for determining different angular relation between the units.
- 15 2. A chair comprising a first unit embodying front legs, a seat and back; a second rear leg unit, said first unit having a pair of guide slots, said second unit having rod means coacting with the guide slots, there being additional downwardly open, laterally adjacent slots provided by the first unit, and additional rod means carried by the second unit effective on relative shifting of the units to coact in different downwardly open slots to change the seat position.
- 25 3. In witness whereof I affix my signature.

JOHN A. SCHAUSS.
